UNITED STATES PATENT OFFICE.

JAMES ROBBERT GRAVES REEVES, OF MCCOMB, MISSISSIPPI.

CULTIVATOR.

SPECIFICATION forming part of Letters Patent No. 446,538, dated February 17, 1891.

Application filed September 26, 1890. Serial No. 366,261. (No model.)

To all whom it may concern:

Be it known that I, JAMES ROBBERT GRAVES REEVES, a citizen of the United States, residing at McComb city, in the county of Pike 5 and State of Mississippi, have invented certain new and useful Improvements in Cultivators; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 Figure 1 is a top view. Fig. 2 is a side view. Fig. 3 is a section on line 3 3, Fig. 1. Fig. 4 is a detail view.

This invention relates to improvements in cultivators, and has for its object the production of a cultivator whereof the shares will always be at the proper angle, as set forth.

The invention consists in the construction hereinafter set forth.

25 In the annexed drawings, the letter A indicates the cultivator-beam, to the rear end of which are pivoted the handles B B. Secured to the top of the beam between these handles is a curved bar C, having the teeth 30 d on each side. Passing under the bar C and through the handles is the bolt b. By this arrangement the handles can be adjusted to any position and clamped against the teeth by drawing on the bolt b. The sides of the 35 handles being smooth, the teeth bite into the wood. The shares d are secured to the feet of the standards D, the upper ends d' of the latter being horizontal.

Passing down through the beam A is a bolt E, the lower end e of which rests in a slot f in 40 a curved bar F. This bar F is secured to a main plate G. This plate G has a number of round holes g, and the same number of shares are to be used. The share-standards are secured by bolts h passing up through them and 45 through the holes and slots. After the rear bolts pass through the slots g' they are secured to a strip H, which is pivoted to the beam A. The bolts of one of the share-standards take into the cultivator-beam, and thereby secure the plate and standards to the beam. The slot f is to be of a length determined by the amount of desired play to be given the shares.

It will be seen that in this device the plate 55 carrying the share-standards plays around the bolt E, and that all the shares take the same angle. No matter what position the beam may be given, the shares always come to the proper angle.

Having thus described my invention, what I claim is—

The combination of the shares and their standards, the main plate G, to which the standards are pivoted, such plate having the 65 slots in the rear of the pivots of the standards, the beam A, the strip H, pivoted to the beam, and bolts passing through the slots and securing the rear ends of the standards to the strip H, as set forth.

In testimony whereof I affix my signature in presence of two witnesses.

JAMES ROBBERT GRAVES REEVES.
